UNITED STATES PATENT OFFICE.

CHARLES KAUFMAN, OF CLEVELAND, OHIO.

METHOD OF MAKING SCREWS AND BOLTS.

Application filed September 8, 1925. Serial No. 54,953.

This invention relates to a method of making certain kinds of screws and bolts having an unthreaded portion next to the threads, such as cap screws, machine bolts, carriage bolts, rim bolts, shackle bolts, king pins and the like. The main object of the invention is to provide a method by which better and more accurate screws and bolts of this character are produced. More particularly, it is the aim of the invention to obtain increased strength in that portion of the blank which is to be threaded, and to so form the blanks that they are held to exact dimensions, and so that they can be formed in any lengths desired, and at the same time permit a better and larger head to be formed which does not crystallize or fracture in forming.

These screws and bolts are commonly formed from a length of wire of a diameter corresponding to the pitch diameter of the thread to be formed, and by means of dies a portion of the blank is upset to form the head and also to form an enlarged portion between the head and the portion to be threaded, said enlarged portion being expanded by the upsetting process to the external diameter of the threads which are to be rolled onto that portion of the blank which remains at the original diameter.

Instead of starting with a blank which is of the pitch diameter of the thread to be formed, and then upsetting the stock to enlarge the same to form the unthreaded portion and the head, I start with a length of stock which in diameter corresponds to the diameter of the unthreaded portion of the finished screw or bolt, and reduce that portion of the blank which is to be threaded, the part to be threaded being reduced to the pitch diameter of the thread to be formed. Preferably the reducing of the part to be threaded is accomplished in the same dies and at the same time that the other end of the stock is upset to form the head.

The invention may be further briefly summarized as consisting in the steps of the improved method which will be described in the specification and set forth in the appended claims.

In the accompanying sheet of drawings, Fig. 1 shows a length of wire ready for the forming process; Fig. 2 shows the blank after the stock of Fig. 1 has been treated by

my improved method; Fig. 3 shows the finished screw, in this instance a cap screw; and Fig. 4 shows diagrammatically a pair of dies which may be utilized in carrying out my improved method.

The screw which is produced is of conventional shape or design, and consists of a head 10, a threaded portion 11 and an unthreaded portion 12 between the head and threaded portion. If the threads are formed by a rolling process, as is customary, the portion 12 must be of greater diameter than the portion to be threaded, and as before stated, the head 10 and portion 12 are generally formed by expanding the stock, the original diameter corresponding to the pitch diameter of the threaded portion.

Inasmuch as the head 10 and unthreaded portion 12 are by the commonly employed method both formed by expanding or enlarging the stock, practice has demonstrated that the length of the unthreaded portion is limited, i. e. can not be made in more than a predetermined length for a given size of stock, and inasmuch as the head is formed from a stock of relatively small size, it is generally not perfectly formed and often crystallizes or fractures in the forming.

According to my invention I start with stock or length of wire indicated at 13 in Fig. 1, and produce the blank shown in Fig. 2, by a method wherein the diameter of the portion 15 to be threaded is reduced, while the enlargement 16 to form the head of the finished screw is formed by upsetting the stock of the original diameter. That is to say, if D represents the diameter of the stock 13, this diameter is maintained in the portion 14, while the portion 15 to be threaded, is reduced to a smaller diameter d' , and the head portion 16 is upset to a larger diameter D' .

In carrying out the method I prefer to use male and female dies, indicated conventionally in Fig. 4, wherein 17 represents the female die member and 18 the male die member. The female die member has an irregular cavity including an outer head-forming portion 17^a, then a portion 17^b of reduced diameter which is the same as the diameter D of the stock, and at the base of this there is a still further reduced portion 17^c, which in diameter corresponds to the reduced part 15 of the blank, the diameter of which is represented by the letter d' .

In practice the wire is fed in an indeterminate length from a suitable reel, and is automatically cut into sections of the desired length, and as a section of stock is cut off 5 it is carried over into line with the cavity of die 17, which is the stationary die. The die 18 reciprocates, and as soon as the stock comes into line with the cavity it is struck by the die and driven inward, a portion of 10 the stock being forced into the reduced part 17^c of the cavity so as to form the portion 15 of the blank by reducing the diameter of the stock and lengthening it with an action similar to that which takes place in a drawing or extruding process. The stock is 15 driven into the reduced part 17^c of the cavity until it engages an adjustable stop member or gauge 19 which serves also as an ejector. At the same time that the stock is driven 20 into the die cavity and its inner and reduced as just stated, the outer end is upset into the headforming cavity 17^a so as to form or partially form the head 16. The head may be entirely formed by this same 25 blow of the die or plunger 18, but generally the stock is given a second blow to complete the formation of the head, after which the blank is ejected.

By this method the reduced part 15^a of the 30 blank is given a skin or surface hardening characteristic of drawn or extruded material, which makes it very desirable for screw forming purposes, and inasmuch as the portion 14 retains its original diameter, it is, 35 of course, possible to make this of any length, as is true also of the reduced part 15. On the contrary, by the old method wherein the diameter of the portion 14 is formed by the 40 upsetting process, the length of the unthreaded portion of the blank is limited. Furthermore, since the diameter of the portion 16 is unchanged, and the portion 15 formed by driving the stock into the reduced 45 part of the die cavity, it is obvious that the blanks can be turned out, one after another, with the portions 14 and 15 held to the exact dimensions desired, which is not always 50 the case with the prior process, and since the head 16 is formed from stock of a larger diameter than is used with the old process in forming a given sized screw, there is less likelihood of crystallization and fracture in forming the head.

In brief, therefore, by my method above 55 described, I am able to produce better and more accurate screws or bolts than heretofore, with a minimum loss on account of defective blanks, and with any desired length of unthreaded portion, and at the same time the 60 blanks can be produced with the same or greater rapidity than by the prior methods.

After the blank described above, and illustrated in Fig. 2, is formed, the screw is finished by converting, by the usual process, 65 the annular head 16 to an octagonal or other

polygonal shape desired if the type of screw requires it, and by forming the thread 11 on the reduced part 15 of the blank, generally by rolling the thread thereon.

As already stated, the stock from which 70 the screws are formed corresponds in size to the diameter of the unthreaded portion, but the stock may have a slight oversize or undersize tolerance. If it is slightly oversized, the stock will be forced into the die cavity by 75 the plunger 18 slightly reducing the stock to the amount of the tolerance to form the portion 14 of the blank. If the stock is slightly undersized, the stock is slightly enlarged to completely fill the portion 17^b of 80 the die cavity. Generally the original diameter D of the stock is maintained in the portion 14 of the blank, but as stated above, a slight variation in the size of the stock, either oversize or undersize will have no material effect on the method since the most important feature of the invention is the reduction and lengthening and consequent hardening of that part of the stock which is 85 to be threaded.

While I have illustrated my method applied to the production of cap screws, it can be used just as effectively for forming other types of screws and bolts such as those mentioned in the early part of the specification. While I have described the preferred method of carrying out my invention, I do not desire to be confined to the precise details shown, but aim in my claims to cover 90 all modifications which do not involve a departure from the spirit and scope of my invention.

Having described my invention, I claim:

1. The method of making screws and bolts, which comprises upsetting one end of 105 a length of stock to form the head portion and in the same operation drawing out and thereby lengthening and reducing another portion to the pitch diameter of the thread to be formed by forcing the stock endwise 110 into the opening of a drawing die, and forming the thread on said portion.

2. The method of making screws and bolts, which comprises forcing a piece of stock by pressure exerted endwise thereon into 115 the opening of a drawing die to draw out and thereby reduce and lengthen the portion which is to be threaded, and in the same operation upsetting upon one end an enlarged head portion, and thereafter forming the thread on said reduced portion.

3. The method of making screws and bolts, which comprises forcing a piece of stock by pressure exerted endwise thereon into the 125 opening of a drawing die to draw out and thereby reduce and lengthen the portion which is to be threaded, and in the same operation upsetting upon one end an enlarged head portion and retaining a portion between 130 the reduced portion and the enlarged head

portion of substantially the same diameter after forming the thread upon said reduced as the diameter of the piece of stock, and thereafter forming the thread upon the reduced portion.

5. 4. The method of making screws and bolts, which comprises forcing a piece of stock by pressure exerted endwise thereon into the opening of a drawing die to draw out and thereby reduce a portion to a diameter substantially equal to the pitch diameter of the thread to be formed, and in the same operation upsetting an enlarged head portion upon one end but retaining a portion between the reduced portion and the enlarged head
- 10
- 15
- portion of a diameter substantially equal to the diameter of the piece of stock, and there-

5. The method of making screws and bolts, which comprises forcing a piece of round wire or rod by pressure exerted endwise thereon into the opening of a drawing die to draw out and thereby reduce the portion to be threaded, and in the same operation upsetting an enlarged head portion upon one end but retaining an intermediate portion of a diameter substantially equal to the diameter of the wire or rod, and thereafter rolling a thread upon said reduced portion.

In testimony whereof, I hereunto affix my signature.

CHARLES KAUFMAN.
